MACHINE AND METHOD FOR MAKING
GARMENT HANGERSLeonard A. Young, Detroit, Mich., assignor to
Bowen Products Corporation, Ecorse, Mich.

Application November 18, 1940, Serial No. 366,138

32 Claims. (Cl. 93—82)

The main objects of this invention are:

First, to provide a machine or apparatus for making curved tubes from webs of paper which is of large capacity and very efficient in that it economically produces a strong uniform product.

Second, to provide a machine or apparatus having these advantages which requires a minimum of care and attention on the part of the operator or attendant.

Third, to provide a machine of the character described which is suitable for making tubular curved members adapted for use as the garment supporting yoke of garment hangers.

Fourth, to provide a method of producing curved tubes from webs of paper which may be carried on as a continuous operation, and one in which the stock, a web of paper, is not subjected to rupturing stresses during the steps of manufacture.

Fifth, to provide a method of the character described which enables the economical production of a relatively stiff and rigid product well adapted for various uses and particularly well adapted for use in the manufacture of garment hangers.

Objects pertaining to details and economies of the invention will definitely appear from the description to follow. The invention is defined in the claims.

A structure which embodies the features of the invention and the manner of carrying out the method is clearly illustrated in the accompanying drawings, in which:

Fig. 1 is a perspective view of a machine for the manufacture of paper tubes and illustrating one apparatus suitable for practicing my method.

Fig. 2A is a diagrammatic view illustrating certain of the steps of my method between the roll of web paper stock and the formed and curved tube.

Fig. 2B is a diagrammatic view illustrating the remainder of the steps of the method, being a continuation of the showing of Fig. 2A at the broken line appearing in these figures.

Fig. 2C is a fragmentary top plan view somewhat conventionalized illustrating certain of the steps of the method.

Fig. 3 is a side elevation of a length of the curved tube suitable for use in forming a garment hanger yoke.

Fig. 4 is a side elevation of a garment hanger in which the yoke is formed from a section of tubing such as shown in Fig. 3.

Fig. 5 is a fragmentary view illustrating cer-

tain of the steps in the handling of the stock prior to forming into tubular form.

Fig. 6 is an enlarged view in section on line 6—6 of Fig. 5.

Figs. 7 to 12, inclusive, are views illustrating successive steps and portions of the machine by which the multi-ply strip or web is formed into tubular form.

Fig. 13 is a fragmentary view in longitudinal section illustrating certain portions of the tube curving apparatus.

The embodiment of my invention illustrated is designed for use in producing curved paper tubing suitable for use in forming curved yokes for garment hangers, primarily ladies' garment hangers or other hangers where struts or cross bars are not desired. Such hangers in which the yokes are formed of wood or wire have been in use, but one of the aims of the present invention is to provide a yoke or hanger member of the proper curvature to which a suspending hook may be easily attached, and formed in its entirety of relatively inexpensive paper stock which when completed is strong and rigid and at the same time light in weight. An additional advantage of a hanger yoke of this character is that it retains the garments more effectively than wood or wire, that is, there is a substantial resistance to the tendency of the light garments or the supporting straps thereof for sliding off the hanger.

In my Patent 2,203,006 issued June 4, 1940, I describe a method of forming paper tubes embodying certain of the steps of my present invention. The method and apparatus disclosed in that patent is designed primarily for the manufacture of paper tubes for use as struts in garment hangers in which the yoke is formed of wire.

A further feature of importance in the present invention is that the tube forming operation is such that substantially no lateral or longitudinal stresses are imposed on the material or stock during the manipulation thereof into a multi-ply web or forming the same into tubular form. This permits the use of a relatively inexpensive or low grade of stock without the finished product being objectionably weak or having weak spots or zones.

Referring to the accompanying drawings, I illustrate in Fig. 1 a machine adapted for the complete forming of the curved tubes from a web of paper. The cutting off mechanism used when it is desired to divide the tube into sections suitable for garment hangers illustrated is not shown. While the machine illustrated is

highly desirable for practicing my method, I recognize that my method may be practiced by a great variety of apparatus.

In the embodiment illustrated the main frame 1 is provided with a superstructure 2 including a laterally extending support 3 on which are mounted certain of the operating instrumentalities. The completed curved tube is indicated by the numeral 4 at the right of Fig. 1, while the frame 5 serves as a support for the web of paper stock 6 at the front end of the machine. The apparatus is driven from a motor 7 through various operating connections which are not described as the invention is not limited or directed to such details of construction.

In Figs. 2A, 2B and 2C I illustrate diagrammatically the entire procedure in accordance with the method of my invention. The web 6 is led from the supply roll over a suitable idler 8 and past a slitting couple generally indicated 9, whereby the web is subdivided longitudinally into parallel portions 61, 62, as illustrated in Fig. 5. Following said subdivision the webs 61, 62 pass through a pair of driving rollers generally designated 10, thence upwardly over an idler 11 and between a gluing roller 12 and a coating support roller 13, the gluing roller engaging with a supply roller 14 mounted in a suitable tank 15 and being disposed beneath the advancing webs 61, 62. Roller 12 applies adhesive 63 to the webs 61, 62 in parallel bands as illustrated in Fig. 5. This adhesive is of a quick drying nature and the paper is preferably of such an open fibered character that a substantial penetration of the adhesive takes place in addition to the surface coating for adhering webs 61, 62 to one another and so as to enhance the stiffness of the completed article when dry. It will be noted that the wider of the two parallel webs has a longitudinal border portion 64 left free from the application of adhesive.

Following gluing of the webs, the same are superposed on one another in the manner illustrated in Fig. 5, this operation being performed by passing the web 61 rearwardly around an idler 16 which is canted at an angle to the horizontal and serves to direct web 61 onto the web 62 at the glued portion thereof, two corresponding edges of the superposed webs being flush with one another following said overlapping.

The superposed webs next traverse a scoring couple 17 comprising rollers having coacting male and female scoring members adapted to impart the spaced parallel score lines 65 to the superposed webs, as illustrated in Figs. 5 and 6, thus preparing the same for folding during the further longitudinal advance of the webs. One of the score lines is disposed substantially medially of the overlapped superposed webs, while the other falls along the edge of the top web 61. In order to prevent undue gumming and clogging of the scoring roll which engages the glued side of the web I provide a suitable wiper 18 which, like the scoring couple, is suitably mounted on the superstructure 2. This wiper prevents accumulation and hardening of the glue solution on the scoring roller.

Following scoring, the web passes to a folding way comprising a plurality of folding arms 19 acting to direct the various parallel portions of the scored web into folded relation in the manner clearly illustrated in Fig. 7. The web emerges from the folding way in the relatively flat section illustrated in Fig. 8 and next enters the bight of a pair of driven coacting male and female form

rollers 20, 21, respectively, whereby the multi-ply folded strip resulting from the operation of the folding way is given an initial conformation toward its ultimate tubular outline by bending the edges thereof downwardly as shown in Fig. 9. The form rollers 20, 21 at the same time serve to advance the web through the subsequent successively acting concave forming roller pairs 22, 23, 24, it being appreciated that the two rollers of each of these pairs are respectively identical and act on the sides of the initially conformed web issuing from rollers 20, 21 to progressively bend the same in the manner illustrated in Figs. 10, 11, and 12 until the opposite edges of the multi-ply strip are brought into abutting relation, as illustrated in Fig. 12, leaving the unglued longitudinal portion 64 on one edge to overlap the other edge externally of the tube. During passage through the pairs 22, 23, 24 this overlapping portion 64 has adhesive applied thereto by means of a suitable applicator 25 supplied from a tank 26. The tube then passes through a series of coacting concave roller pairs generally designated 27 by which the overlapping glued flap is pressed onto the exterior of the opposite abutting edge and firmly adhered thereto to hold the advancing stock in its tubular form.

The various successively acting web folding and tube forming or rolling instrumentalities referred to above are appropriately mounted in any suitable manner on the laterally extending support 3 of the superstructure 2, as illustrated in Fig. 1. The particular roller mountings employed have not been illustrated in detail, since they form no part of the present invention; however, appropriate provisions to this end will readily suggest themselves to those skilled in the art.

As the stock in its completed form issues from the finish roller pairs 27, it enters a bending and setting device which is generally designated 28 in Fig. 1. This device comprises a suitable bracket-like support in the form of a pair of spaced plates 29 secured in an appropriate manner to the support 3 and extending rearwardly beyond the same and downwardly. One of the plates 29 has rotatably mounted thereon the alternate pairs of horizontally and vertically journaled coacting concave surfaced bending and setting rollers 30, 31, respectively, these pairs being successively arranged in the outline of an arc. The foremost of the horizontally journaled pairs, specially indicated by the reference numeral 301 in Figs. 1 and 13, has the lower roller thereof mounted on a shaft 302 provided with a gear 303 indicated in dotted lines in Fig. 13. This gear is driven by a suitable meshing driver 304 also shown in dotted lines in Fig. 13, to advance the formed tube through the bending-setting device in a positive manner.

The next successive pair of horizontally journaled bending and setting rollers, particularly designated by the reference numeral 305 in Fig. 13, is provided with diametrically spaced embossing projections 306 in the concave surface of the lower roller 307 of the pair, which projections are operable on the tube as it passes between this couple to form spaced indentations 308 in the bottom side thereof and thereby facilitate bending of the tube to curvilinear outline. Roller 307 is provided with a driving gear 309 in mesh with idler 304 and the remainder of the horizontally journaled pairs are also provided with appropriate driving gears (not shown), suitable idlers likewise not shown being employed to drivingly connect these gears. The driving and

idler gears are all preferably mounted in the space between plates 29.

Disposed beneath the initial pairs of bending and setting couples 30, 31 is a gas burner 32 or other suitable heating or drying device, the burner being supplied with heating medium through a connection 32' whereby in passing through the setting roller the tube is heated somewhat so as to expedite drying and setting of the adhesive impregnating the same and holding the tube in desired outline.

As stated, the successive pairs or couples 30, 31 are arranged in arcuate disposition, as clearly illustrated in Figs. 1 and 2, with the result that the tube is given a permanent set in curvilinear outline as it passes through these couples and is indented, bent and set by drying in the device 28. This curvilinear outline is maintained by means of further spaced and opposed concave idlers 33 mounted on an arcuate extension 34 secured to support 29, the said idlers 33 being disposed alternately on opposite sides of the curved tube to guide the same in a helical path to its point of discharge in the finished form indicated by the reference numeral 4 in Fig. 1. At this point the tube is cut in appropriate lengths of from 15 to 17 inches. The radius of curvature of the tube contemplated by the invention is approximately 36 inches and the arc in which the bending roller pairs 30, 31 are disposed is arranged accordingly.

It should be noted that the tube is curved with the joint on the concave side of the tube, and that the spaced indentations in the tube extend transversely across the joint. This greatly facilitates the curving step and the curving step does not tend to open up the joint; in fact, there is a tendency to close the joint or urge the abutting edges toward each other. While with the transverse scoring or indenting the tube may be bent with the joint otherwise positioned, this positioning of the joint on the concaved side of the tube is very desirable as a step of manufacture. The tube is thus conformed to the desired curvature prior to the setting of the adhesive and is maintained in this curvature until the adhesive is substantially set, when the tube becomes rigid and does not tend to distort or straighten. Using the multi-plies adhesively secured together provides a structure in which the adhesive, serving not only to bind the parts together but as a stiffening agent, is quite uniformly distributed throughout. The result is a rigid structure and a structure which is very economical to produce, both in material and labor factors.

Following production of the tube lengths or yokes in the manner described, the latter are pinched or compressed at the ends 35 thereof and the suspending hanger 36 is attached in any suitable fashion to provide the finished garment hanger. This is an extremely light and inexpensive article well adapted for supporting ladies' garments, inasmuch as the material thereof permits the pinning of garments thereto. The hanger is amply strong for its intended purposes by reason of the folded multi-ply and rolled tubular construction, impregnated with adhesive which strongly resists bending or collapse.

It will be evident that the indenting of the bottom of the tube in the manner described while forwarding and setting the same greatly facilitates the bending and setting thereof in its desired curvilinear outline.

I have illustrated and described my improvements in an embodiment which is very practical.

I have not attempted to illustrate or describe other embodiments or adaptations as it is believed this disclosure will enable those skilled in the art to embody or adapt the invention as may be desired.

Having thus described my invention, what I claim as new and desire to secure by Letters Patent is:

1. In a machine for forming curved paper tubes, the combination of means for continuously advancing a web of fibrous stock and subdividing said web longitudinally to provide a plurality of parallel webs, means for applying adhesive to said webs, means for superimposing said webs one upon the other while advancing the same and adhesively securing them together, means for advancing and folding said superimposed webs to adhesively secured multi-ply form, a series of conforming rollers successively acting on said multi-ply formed web and conforming it into a tube, means for curving the tube as it is advanced and to which it is delivered prior to the setting of the adhesive, comprising a series of pairs of tube curving rollers disposed in a circular path, one of said rollers being disposed on the concave side of such curved path and being provided with a tooth-like tube indenting or crimping member which forms spaced transverse indentations in the concaved side of the tube as it is advanced, the tube being presented to said tube curving rollers so that the joint thereof is on the concave side of the tube and so that the indentations extend transversely of the joint, and means for maintaining the tube in its curved form until the adhesive is substantially set.
2. In a machine for forming curved paper tubes, the combination of means for forming a multi-ply web of adhesively secured plies, a series of conforming rollers successively acting on said multi-ply formed web and conforming it into a tube, means for curving the tube as it is advanced and to which it is delivered prior to the setting of the adhesive, comprising a series of pairs of tube curving rollers disposed in a circular path, one of said rollers being disposed on the concave side of such curved path and being provided with a tooth-like tube indenting or crimping member which forms spaced transverse indentations in the concaved side of the tube as it is advanced, the tube being presented to said tube curving rollers so that the joint thereof is on the concave side of the tube and so that the indentations extend transversely of the joint, and means for maintaining the tube in its curved form until the adhesive is substantially set.
3. In a machine for forming curved paper tubes, the combination of means for forming a multi-ply web of adhesively secured plies with one ply projecting beyond the multi-plies to provide a joint flap, means for applying adhesive to said joint flap, means for forming said multi-ply web into a tube with the edges thereof in abutting relation and with the joint flap on the outside thereof and adhesively secured, and means for curving the tube prior to the setting of the adhesive, comprising a roller disposed on the concave side of such curved path and provided with a tooth-like tube indenting or crimping member which forms spaced transverse indentations in the concaved side of the tube as it is advanced, the tube being presented to said tube curving means so that the joint thereof is on the concave side of the tube and so that the indentations extend transversely of the joint.
4. In a machine for forming curved paper

tubes, the combination of means for forming a multi-ply web of adhesively secured plies, means for forming said multi-ply web into a tube with the edges thereof in abutting relation, and means for curving the tube prior to the setting of the adhesive, comprising a roller disposed on the concave side of such curved path and provided with a tooth-like tube indenting or crimping member which forms spaced transverse indentations in the concaved side of the tube as it is advanced, the tube being presented to said tube curving means so that the joint thereof is on the concave side of the tube and so that the indentations extend transversely of the joint.

5. In a machine for forming curved paper tubes, the combination of means for forming a multi-ply web of adhesively secured plies, means for forming said multi-ply web into a tube with the edges thereof in abutting relation, and means for curving the tube prior to the setting of the adhesive, comprising a roller disposed on the concave side of such curved path and provided with a tooth-like tube indenting or crimping member which forms spaced transverse indentations in the concaved side of the tube as it is advanced.

6. In a machine for forming curved paper tubes, the combination of means for forming a multiply-ply web of adhesively secured plies with one ply projecting beyond the multi-plies to provide a joint flap, means for applying adhesive to said joint flap, means for forming said multi-ply web into a tube with the edges thereof in abutting relation and with the joint flap on the outside thereof and adhesively secured, and means for curving the tube prior to the setting of the adhesive, the tube being presented to said tube curving means so that the joint thereof is on the concave side of the tube.

7. In a machine for forming curved paper tubes, the combination of means for forming a multi-ply web of adhesively secured plies, means for forming said multi-ply web into a tube with the edges thereof in abutting relation, and means for curving the tube prior to the setting of the adhesive, the tube being presented to said tube curving means so that the joint thereof is on the concave side of the tube.

8. A machine for forming paper tubes, comprising means for supporting and advancing a web of paper, means for applying adhesive to the advancing web, means for laterally folding into a multi-ply web and rolling the adhesive bearing multi-ply web to tubular cross section as advanced to a discharge point, means at the discharge point of said folding and rolling mechanism to guide the advancing tube into a curvilinear path, means adjacent said discharge point to indent the concave side of the tube to facilitate the curving thereof, and means to expedite drying the adhesive of the web to set the latter in curvilinear outline.

9. A machine for forming paper tubes, comprising means for advancing fibrous web material, means for applying adhesive to said material, means for assembling said material in multi-ply form, means for conforming said multi-ply material to tubular section while advancing the same, means for guiding the advancing tube in a curvilinear path to thereby form it into a curvilinear outline, and means through which said tube advances for maintaining the same in such curved outline while advancing until the adhesive is substantially set, said last

named means delivering the curved tube on the discharge side thereof.

10. A machine for forming paper tubes, comprising means for advancing a reinforced length of fibrous bendable stock, and means to guide the advancing stock in a curvilinear path of the desired radius, comprising spaced opposed co-acting guide members disposed in an arcuate series, including pairs of members respectively engaging opposite convex and concave sides of the stock to conform and set the stock in such curvilinear outline as it advances.

11. The steps in forming curved paper tubes, comprising advancing a web of fibrous stock and subdividing said web longitudinally to provide a plurality of parallel webs, superimposing said webs one upon the other while advancing the same and adhesively securing them together with a portion of one of the superimposed webs projecting beyond the edge of the other providing a joint flap, advancing and folding the superimposed webs to multi-ply form, conforming such multi-ply form into a tube with the joint flap on the outside thereof and adhesively secured, curving the tube with the joint on the convex side of the tube and prior to the setting of the adhesive and simultaneously with the curving forming spaced transverse indentations in the concave side and extending across the joint, and maintaining in curved form until the adhesive is substantially set.

12. The steps in forming curved paper tubes, comprising advancing a web of fibrous stock and subdividing said web longitudinally to provide a plurality of parallel webs, superimposing said webs one upon the other while advancing the same and adhesively securing them together, advancing and folding the superimposed webs to multi-ply form, conforming such multi-ply form into a tube, curving the tube with the joint on the convex side of the tube and prior to the setting of the adhesive and simultaneously with the curving forming spaced transverse indentations in the concave side and extending across the joint, and maintaining in curved form until the adhesive is substantially set.

13. The steps in forming curved paper tubes, comprising advancing a web of fibrous stock and subdividing said web longitudinally to provide a plurality of parallel webs, superimposing said webs one upon the other while advancing the same and adhesively securing them together with a portion of one of the superimposed webs projecting beyond the edge of the other providing a joint flap, advancing and folding the superimposed webs to multi-ply form, conforming such multi-ply form into a tube with the joint flap on the outside thereof and adhesively secured, and curving the tube with the joint on the convex side of the tube and prior to the setting of the adhesive.

14. The steps in forming curved paper tubes, comprising advancing a web of fibrous stock and subdividing said web longitudinally to provide a plurality of parallel webs, superimposing said webs one upon the other while advancing the same and adhesively securing them together, advancing and folding the superimposed webs to multi-ply form, conforming such multi-ply form into a tube, and curving the tube with the joint on the convex side of the tube and prior to the setting of the adhesive.

15. The method of forming curved paper tubes, comprising the steps of forming a multi-ply web of adhesively secured plies with one ply

projecting beyond the multi-plies to provide a joint flap, forming said multi-ply web into a tube with the edges thereof in abutting relation and with the joint flap on the outside thereof and adhesively secured, forming spaced indentations transversely of the joint and curving the tube with the transverse indentations on the concaved side of the tube, and maintaining the tube in its curved form until the adhesive is substantially set.

16. The method of forming curved paper tubes, comprising the steps of forming a multi-ply web of adhesively secured plies with one ply projecting beyond the multi-plies to provide a joint flap, forming said multi-ply web into a tube with the edges thereof in abutting relation and with the joint flap on the outside thereof and adhesively secured and curving the tube with the joint on the concaved side of the tube, and maintaining the tube in its curved form until the adhesive is substantially set.

17. The method of forming curved paper tubes suitable for garment hanger yokes, comprising forming a multi-ply web of adhesively secured plies of paper with one ply thereof projecting beyond the multi-plies to provide a joint flap, rolling said web longitudinally into a tube with the joint flap extending across the joint and adhesively secured, and curving the tube prior to the setting of the adhesive with the joint on the concaved side of the tube, the curving step including the forming of uniformly spaced indentations extending transversely across the joint.

18. The method of forming curved paper tubes suitable for garment hanger yokes, comprising forming a multi-ply web of adhesively secured plies of paper with one ply thereof projecting beyond the multi-plies to provide a joint flap, rolling said web longitudinally into a tube with the joint flap extending across the joint and adhesively secured, and curving the tube prior to the setting of the adhesive.

19. The method of forming curved paper tubes suitable for garment hanger yokes, comprising forming a multi-ply web of adhesively secured plies of paper, rolling said web longitudinally into a tube having a joint extending longitudinally thereof, and curving the tube prior to the setting of the adhesive with the joint on the concaved side of the tube, the curving step including the forming of uniformly spaced indentations extending transversely across the joint.

20. The method of forming curved paper tubes suitable for garment hanger yokes, comprising forming a multi-ply web of adhesively secured plies of paper, rolling said web longitudinally into a tube having a joint extending longitudinally thereof, and curving the tube prior to the setting of the adhesive with the joint on the concaved side of the tube.

21. The method of forming curved paper tubes, comprising advancing a pair of superposed webs of fibrous stock, folding said advancing superposed webs to flat multi-ply form, successively rolling the advancing multi-ply web to tubular form, adhesively securing said tube in rolled tubular form, continually bending the advancing tube by restraining the same to a curvilinear path prior to the complete setting of the adhesive, and, simultaneously with said bending, indenting the concave side of the tube.

22. In the manufacture of curved paper tubes suitable for yokes for garment hangers, the

steps of continuously advancing web stock and while advancing the latter assembling the same in multi-ply superposed form and rolling the resultant multi-ply stock to tubular section, and thereafter bending the same during its advance by indenting one side thereof at spaced intervals and confining the path of the advance to a curved outline.

23. In the manufacture of curved paper tubes suitable for yokes for garment hangers, the steps of continuously advancing a length of stock, folding the stock on itself and forming the same into tubular section while it is advancing, and bending the so formed tube during its advance by indenting one side thereof at spaced intervals and confining the path of the advance to a curved outline.

24. In the manufacture of curved paper tubes, the steps of assembling plies of fibrous stock in superposed relation, advancing and conforming said plies to provide a relatively stiff tubular length of fibrous stock, indenting one side thereof at spaced intervals during the advance, and confining the path of the advancing indented tube to a curved outline to set the tube in an arcuate curvilinear configuration with the indentations on the concave side thereof.

25. In the manufacture of curved paper tubes, the steps of assembling and advancing plies of fibrous material to provide an elongated length of fibrous multi-ply stock, forming said multi-ply stock while advancing into a tube, and confining the path of the advancing tube to a curved outline to set the tube in an arcuate curvilinear configuration.

26. In the manufacture of curved paper tubes, the steps of assembling and advancing plies of fibrous material to provide an elongated length of fibrous multi-ply stock, forming said multi-ply stock while advancing into a tube, and indenting one side of the tube at spaced intervals during the advance to set the tube in an arcuate curvilinear configuration with the indentations on the concave side thereof.

27. The method of forming garment hanger yokes, comprising advancing an adhesive bearing web, folding the web longitudinally upon itself to provide a multi-ply section and rolling the same to tubular cross section during the advance thereof, subsequently directing the advancing tube through a confined arcuate path to impart a curvilinear outline thereto, and during the last named operation indenting the tube on a side thereof to facilitate bending and heating the tube to expedite setting of the adhesive thereon to maintain said curvilinear outline.

28. The method of forming garment hanger yokes, comprising advancing an adhesive bearing web, folding the same on itself while advancing and forming the resultant multi-ply web into a tube, directing the advancing tube through a confined arcuate path to impart a curvilinear outline thereto, and heating the tube to expedite setting of the adhesive thereon to maintain said curvilinear outline.

29. The method of forming tubes, comprising advancing an adhesive bearing web, folding and forming the same to multi-ply, reinforced tubular cross section during the advance thereof, directing the advancing tube through a confined arcuate path to impart a curvilinear outline thereto, and during the last named operation heating the tube to expedite setting of the adhesive thereon to maintain said curvilinear outline.

30. The method of forming tubes, comprising advancing an adhesive bearing web, folding and forming the same to multi-ply, reinforced tubular cross section during the advance thereof, indenting the advancing tube to impart a curvilinear outline thereto, and heating the tube to expedite setting of the adhesive thereon to maintain said curvilinear outline.

31. The method of forming a garment hanger yoke, comprising advancing an elongated web of stock, forming the same while advancing by folding and pressing the web on itself and conforming the resultant multi-ply web while advancing into a tube, confining the path of the so formed

advancing tube to a curvilinear outline, and indenting one side of the tube to facilitate permanent setting of the tube in curvilinear outline.

32. The method of forming a garment hanger yoke, comprising advancing an elongated moistened web of stock, forming the same while advancing by folding and pressing the web on itself and conforming the resultant multi-ply web while advancing into a tube, confining the path of the so formed advancing tube to a curvilinear outline, and heating the advancing tube to expedite drying and permanent setting of the tube in curvilinear outline.

LEONARD A. YOUNG.
